Primary Examiner — Kendra Leslie Hamilton*Assistant Examiner* — Jameson P Carey(57) **CLAIM**

An ornamental design for a dental elevator substantially as shown and described.

DESCRIPTION

FIG. 1 is a perspective view of the dental elevator;

FIG. 2 is a side view thereof;

FIG. 3 shows a second side view thereof; and,

FIG. 4 shows a bottom view thereof.

The claim also includes a second embodiment of the dental elevator that is a mirror image of FIGS. 1-4.

The broken lines shown in the drawings represent portions of the dental elevator that form no part of the claimed design.

1 Claim, 4 Drawing Sheets(56)
